DESIGN FOR A CASING FOR VACUUM CLEANERS

Theodore A. Schaad, Detroit, Mich., assignor to
Eureka Vacuum Cleaner Company, Detroit,
Mich., a corporation of Michigan

Application January 20, 1936, Serial No. 60,687

Term of patent 14 years

To all whom it may concern:

Be it known that I, Theodore A. Schaad, a citizen of the United States of America, residing at Detroit, in the county of Wayne and State of Michigan, have invented a new, original, and ornamental Design for a Casing for Vacuum Cleaners, of which the following is a specification, reference being had therein to the accompanying drawing, forming a part thereof, in

which Figure 1 is a perspective view of a casing for vacuum cleaners showing my new design; Figures 2 and 3 are respectively a front elevation and a plan view thereof.

I claim:

The ornamental design for a casing for vacuum cleaners, substantially as shown.

THEODORE A. SCHAAD.
